WINDING ARBOR

Harold R. Longfellow, Baltimore, Md., assignor to
 Western Electric Company, Incorporated, New
 York, N. Y., a corporation of New York

Application May 6, 1950, Serial No. 160,543

10 Claims. (Cl. 242—72)

1

This invention relates to winding arbors, and more particularly to collapsible arbors used for winding flexible material into pads.

Frequently it is desirable to wind a plurality of strips of paper upon an arbor into individual coiled pads. Usually it is desirable to wind the paper strips tightly around the arbor in order to form firm, self-supporting pads that may be used with apparatus designed to pay-off a paper strip from such a pad. In order to remove tightly wound pads from an arbor without damaging them, it is proposed to make portions of the arbor collapsible to reduce the cross-sectional area thereof.

An object of the invention is to provide new and improved winding arbors.

Another object of the invention is to provide new and improved collapsible arbors for winding flexible materials into pads.

A further object of the invention is to provide an improved arbor for winding machines whose circumference and bearing area can be changed so that pads can be readily wound on and removed from the arbor.

A winding arbor embodying certain features of the invention may include an elongated winding element having a discontinuous portion in the surface thereof and a transverse bore communicating with said discontinuous portion, a segmental member positioned in said discontinuous portion, an actuating member positioned in said bore, and means for engaging said actuating member to move said segmental member into and out of alignment with the external surface of said winding element.

Other objects and advantages of the invention will appear from the following detailed description of an arbor forming a specific embodiment thereof, when read in conjunction with the appended drawings, in which:

Fig. 1 is a plan view of an arbor embodying certain features of the invention;

Fig. 2 is an elevation of an element forming a part of the arbor shown in Fig. 1;

Fig. 3 is an enlarged transverse section taken along line 3—3 of Fig. 1;

Fig. 4 is a transverse section similar to Fig. 3 showing some of the elements of the arbor in different positions;

Fig. 5 is an enlarged transverse section taken along line 5—5 of Fig. 1;

Fig. 6 is an enlarged fragmentary transverse section showing the manner in which flexible material is clamped to the arbor;

Fig. 7 is an enlarged transverse section of a

2

winding arbor forming an alternate embodiment of the invention, and

Fig. 8 is an enlarged transverse section of a winding arbor forming still another embodiment of the invention.

Referring now in detail to the drawings, a winding arbor shown therein includes a rod 10 having a cylindrical winding portion 11 and journal ends 12—12 designed to fit in bearings of a winding machine (not shown), which is arranged to rotate the arbor and wind a plurality of paper tapes 13—13 shown in Fig. 6, into coiled pads 14—14 (Fig. 1). The winding portion 11 is substantially larger in diameter than the journal ends 12—12, and is provided with diametrically opposed longitudinal grooves 15 and 16 in its winding surface. The groove 15 does not extend the full length of the winding portion 11 of the rod 10, but the groove 16 extends the full length of the winding portion of the rod. The groove 16 is of such depth that the bottom thereof does not extend below the surface of the journal ends 12—12. An elongated segment 18 mounted slidably in the groove 15 has a curved outer surface 20 having a radius equal to the radius of the winding portion 11 of the rod 10. The maximum thickness of the segment 18 is substantially less than the depth of the groove 15 so that when the segment is in its collapsed position (Fig. 4) resting on the bottom of the groove, the surface 20 is positioned well inside the winding periphery of the rod.

A plurality of bores 23—23 (Figs. 1 and 3) communicate with the groove 15 and have counterbored portions 24—24 which communicate with the groove 16. Bushings 27—27 secured to the underside of the segment 18 by screws 28—28 are provided with enlarged heads 30—30 slidably mounted in the counterbores 24—24 and body portions 31—31 slidably mounted in the bores 23—23. The bushings 27—27 are of such length that when the heads 30—30 of the bushings abut the bottom of the counterbores 24—24, the segment 18 is in its winding position, in which the curved surface 20 forms a portion of the cylindrical periphery of the winding portion 11 of the rod 10.

An arcuate bar 35 (Figs. 1 and 3) may be moved laterally into the groove 16 to engage the heads of the screws 28—28 and hold the heads 30—30 of the bushings 27—27 against the bottom of their respective counterbores 24—24, and to fasten the ends of the tapes 13—13 to the rod. The bar 35 is tempered so that its inherent resiliency tends to hold it in a curved shape, as is illustrated

in Fig. 2. End portions 36-36 of the bar are tapered and also are provided with holes 37-37. An outer surface 38 (Fig. 3) of the bar is curved to form a continuation of the winding portion 11 of the rod 10 when the bar is seated in the groove, and the inner portion is provided with a central longitudinal groove 39. One end of the bar is inserted into the groove 16 and under a collar 34 secured to the rod so that it curves outwardly away from the rod. The bar is pressed manually inwardly until it is completely within the groove 16. A spring-clip 40 then is snapped over the right-hand end portion of the rod 10, as viewed in Fig. 1, into tapered sockets 43-43 to lock the bar 35 in the groove 16. The sockets 43-43 locate the clip in a centered position on the rod.

The resiliency of the bar causes it to press against all the screws 28-28 and hold the heads 30-30 of the bushings against the bottom of their respective counterbores 24-24, thereby holding the segment 18 in its winding position. Thus, a circular winding surface (Fig. 3) is maintained throughout the length of the winding portion 11 of the rod 10. The bar 35 is of such size with respect to the groove 16 that sufficient clearance is provided between the bar and the sides and bottom of the groove 16 for clamping the paper tapes 13-13 to the rod 10 of the arbor as seen Figs. 3 and 6. When the arbor is rotated on a winding machine with which it is used, it winds the paper tapes 13-13 into tightly wound, self-supporting pads 14-14. The groove 39 is provided in the inner surface of the bar so that the curved bar may be pressed into the groove 16 against the action of its inherent resiliency. While the assembly of the rod 10, the segment 18 and the winding portion of the bar 35 has been described as being cylindrical in shape, it is preferable to taper the assembly so that the diameter of the winding portion 11 of the rod decreases gradually from left to right, as viewed in Fig. 1. The taper facilitates withdrawal of the bar 35 from the rod 10 when the arbor contains the pads 14-14, and also the withdrawal of the arbor from the pads. The right hand end of the winding portion of the rod 10 between the right end of the groove and the right hand journal 12 is provided with a flat side 45 in the same plane as the longitudinal edges of the groove 15 to reduce the circumference of this portion of the rod.

An extension 47 provided on one end of the rod 10 has a keyway 48 for securing a suitable driving means such as a gear or pulley to the rod 10. Usually, such a driving means is driven by the winding machine to rotate the rod 10 until the diameter of the pads 14-14 builds up sufficiently to drive the rod by contact with a roller advancing the tapes to the rod.

Operation

Let it be assumed that the arbor, having the bar 35 removed from the groove 16, is positioned in a suitable winding machine arranged to wind the tapes 13-13 on the arbor. The arbor is positioned so that the groove 16 is facing upwardly and the ends of the tapes 13-13 are laid side by side across the groove 16 in the rod 10. The bar 35 then is positioned in the groove 16 by inserting one end under the collar 34 so that the bar curves away from the rod 10, and is pressed manually into the groove. The spring-clip 40 is positioned over the right-hand end of the rod 10 so that the open ends thereof rest in the

sockets 43-43 to hold the bar in the groove. When the bar 35 is positioned in the groove 16 in this manner, it clamps the ends of the strips 13-13 to the winding portion 11 of the rod 10 of the arbor, and also holds the heads 30-30 of the bushings 27-27 against the bottom of their respective counterbores 24-24.

When the bushings 27-27 are held in this position, they hold the segment 18 in its winding position. The arbor is rotated by the machine to wind the tapes 13-13 into pads 14-14. The tapes 13-13 are maintained under sufficient tension to make the pads hard and tightly wound on the winding portion of the arbor.

When the pads 14-14 reach a predetermined diameter, the winding of the tapes on the arbor is terminated. The arbor then is lifted out of the winding machine, and is positioned on a suitable workbench (not shown) so that the pads may be removed from the arbor. The spring-clip 40 is removed from the rod 10, and the bar 35 is withdrawn from the groove 16 by placing a hook in the hole 37 in the left-end of the bar 35 and pulling the hook to the left, as viewed in Fig. 1. This permits the segment 18 to be moved back into the groove 15, whereby the periphery of the arbor is reduced. This reduction in the periphery of the winding portion of the arbor permits the arbor to be withdrawn readily from the pads without damage thereto. After the arbor has been withdrawn from the pads, it is replaced in the winding machine so that other tapes 13-13 may be secured to the arbor and wound into pads in the manner described.

Embodiment shown in Fig. 7

Fig. 7 shows a cylindrical winding arbor forming an alternate embodiment of the invention which includes a rod 110, generally like the rod 10 shown in Fig. 1. The rod 110 (Fig. 7) is provided with a winding portion 11 having opposed longitudinal grooves 115 and 116 in its winding surface. A segment 118 positioned in the groove 115 has secured thereto a plurality of bushings 127-127 secured spacedly to the segment by screws 128-128. The bushings 127-127 are mounted slidably in bores 123-123 and counterbores 124-124 in the manner described for the bushings 27-27 of the principal embodiment of the invention. The bushings 127-127 are provided with enlarged heads 130-130. A bar 135, identical in construction with the bar 35 (Fig. 2) is positioned removably in the groove 116 to hold the heads 130-130 of the bushings 127-127 against the bottom of the counterbores 124-124, to hold the segment 118 so that its curved surface 120 forms a continuation of the winding surface of the arbor.

The winding portion 111 of the rod 110 also is provided with a second pair of opposed longitudinal grooves 150 and 151 positioned at right angles to the transverse axis of the grooves 115 and 116. An elongated segment 153 positioned movably in the groove 150 has a plurality of bushings 154-154 secured spacedly to the underside of the segment by screws 155-155 so as to slidably engage bores 156-156 and counterbores 157-157. The bores 156-156 and their respective counterbores 157-157 communicate with the grooves 150 and 151, respectively, and are positioned spacedly in the rod 110 between the bores 123-123 and counterbores 124-124. A curved bar 159, which is identical in construction and shape with the bar 35 shown in Fig. 2, is inserted in the groove 151 to actuate the bushings

in their respective bores so that they abut the bottom of their respective counterbores and hold the segment 153 so that its curved surface 158, forms a continuation of the winding surface of the rod 110 when the bar is seated in the groove.

Operation of embodiment shown in Fig. 7

The rod 110 is positioned in the winding machine with the bar 135 removed from its groove 116 but with the bar 159 assembled in its groove 151. The ends of the tapes to be wound on the rod are laid side by side across the groove 116 and the bar 135 is inserted in the groove to clamp the ends of the tapes to the rod 110. It is to be understood that the rod 110 is provided with a collar like the collar 34 and a clip similar to the spring-clip 40 for holding the bars 135 and 159 in their respective grooves. The rod 110 is driven by the winding machine to wind the tapes into tightly wound pads, like the pads 14—14. When the pads reach a predetermined diameter, the winding of the tapes on the arbor is terminated. The rod 110 then is lifted from the winding machine and placed on a suitable work bench so that the bars 135 and 159 may be drawn from the rod in the same manner as that in which the bar 35 is removed from the groove 16. Removal of the bars 135 and 159 from the grooves allows the segments 118 and 153 to move into their respective grooves and thereby reduce the cross-sectional area of the rod 110, whereby the rod 110 may be withdrawn readily from the pads wound thereon without damage to the pads.

Embodiment shown in Fig. 8

Fig. 8 shows a winding arbor forming a further embodiment of the invention, which may include an elongated rod 210 similar to the rod 10 described in the preferred embodiment of the invention. The rod 210 has a central bore 260 extending longitudinally therethrough and opposed keyways 262 and 263 formed therein. Elongated segments 265 and 266 are positioned movably in opposed longitudinal grooves 267 and 270, respectively. A plurality of posts 272—272 having body portions 273—273 and enlarged head portions 274—274 are secured spacedly to the underside of the segment 265. The body portions of the posts 272—272 engage bores 275—275 communicating with the groove 261 and the keyway 262 in the same manner as that in which the bores 23—23 communicate with the groove 15 of the arbor described as the preferred embodiment of the invention. The enlarged head portions of the posts 272—272 slidably engage the keyway 262.

The segment 266 has a plurality of posts 276—276 which are identical in construction to the posts 272—272 secured to the segment 265. The posts 276—276 slidably engage bores 277—277, which communicate with the groove 270 and the keyway 263 and the enlarged head portions of the posts slidably engage the keyway 263. The posts 272—272 and 276—276 are of such length that when the head portions thereof engage the bottom of the keyways 262 and 263, they position the segments 265 and 266 so that their outer curved surfaces 280 and 281 form continuations of the winding surface of the rod.

The rod 210 is provided with a longitudinal groove 283 for slidably receiving a bar 284 which is identical in construction and shape with the bar 35 shown in Fig. 2. The bar 284 is provided with a curved surface 285 which forms a continuation of the winding surface of the rod when the bar is positioned in its groove. The bar 284

is used to clamp the ends of the tapes to the rod 210 in the same manner that the bar 35 clamps the tapes 13—13 to the rod 10. An elongated bar 286 fits slidably in the keyways 262 and 263 and is of such width that when the bar is positioned in the keyways, it holds the posts 272—272 and 276—276 so that their head portions abut the bottom of the keyways 262 and 263. When the posts are held in this position, the outer surfaces 280 and 281 of the segments 265 and 266 form continuations of the winding surface of the rod 210.

Operation of embodiment shown in Fig. 8

The rod 210 is positioned in a suitable winding machine with the bar 286 positioned in the keyways 262 and 263 to hold the segment 265 and 266 in their winding position, but with the bar 284 removed from its groove 283. The ends of the paper tapes to be wound into pads on the arbor are laid side by side across the groove 283. The curved bar 284 then is positioned in the groove 283 and is held in place by a collar like the collar 34 positioned on one end of the rod and a spring-clip like the clip 40 positioned on the other end of the rod. The rod 210 then is rotated to wind the paper tapes into pads, like the pads 14—14. When the pads wound on the rod reach a predetermined diameter, rotation of the arbor is terminated and the arbor then is removed from the machine and placed on a suitable work bench.

The bar 284 is removed from the groove 283 and the bar 286 then is removed from the keyways 262 and 263 to allow the segments 265 and 266 to move toward the bottom of their respective grooves. This movement of the segments reduces the cross-sectional area of the rod 210 so that the rod may be withdrawn from the tightly wound pads without damaging the pads.

While the above-described arbors are particularly well fitted for winding tapes of flexible material into tightly wound, self-supporting pads, each may be used readily for winding a single sheet of flexible material into a tightly wound roll, and may be readily withdrawn from such a roll by the removal of the bar 35 from the arbor in the manner described.

The above-described arbor may be readily modified to suit various types of winding apparatus without departing from the spirit and scope of the invention.

What is claimed is:

1. An arbor for winding flexible material into coils, which comprises an elongated element having a portion upon which coils of such material may be wound, said winding portion having opposed gaps in its winding surface and a transverse bore communicating with the gaps, an elongated segment mounted in one of the gaps of the winding portion of the element and movable generally transversely with respect to the element between a collapsed position and one in which the outer surface of the segment forms a continuation of the winding surface of the element, a thrust member mounted slidably in the bore for moving the segment with respect to the winding portion of the element, and means insertable in the other gap in the winding surface for forming a part of the winding surface of the arbor and for clamping the material to the element and for actuating the thrust member to move the outer surface of the segment into and out of alignment with the winding surface of the element.
2. An arbor for winding flexible material into

coils, which comprises an elongated element having a portion upon which coils of such material may be wound, said winding portion having opposed gaps in its winding surface and a guideway extending transversely therethrough and communicating with said gaps, an elongated segment mounted in one of the gaps of the winding surface of the element and movable generally transversely with respect to the element between a collapsed position and one in which the outer surface of the segment forms a continuation of the winding surface, a thrust member mounted slidably in the guideway for moving the segment with respect to the winding portion of the element, means insertable in the other gap in the winding portion for clamping the ends of the material to the element and for forming a continuation of the winding surface and actuating the thrust member to hold the segment in such a position that the outer surface thereof is flush with the winding surface of the element and removable from the gap to collapse the segment on the winding portion of the element, and means for selectively holding the thrust-actuating means on the winding portion while the material is wound thereon and for releasing the thrust-actuating means so that it may be removed from the winding portion after the material is wound thereon.

3. An arbor for winding flexible material into coils, which comprises an elongated cylindrical body having a gap in its winding surface, an elongated segment positioned in the gap to fill in substantially the discontinuity in the winding surface and movable generally transversely between a collapsed position and an expanded position in which the outer surface of the segment forms a continuation of the winding surface of the body, said body having a longitudinal groove in its winding surface diametrically opposed to the movable segment and a bore communicating with the gap in the winding surface and the groove, a thrust element attached to the segment and mounted slidably in the bore for moving the segment with respect to the body, a bar insertable in the groove for moving the thrust element to such a position that it holds the segment so that its outer surface is aligned with the winding surface of the body, and means attachable to the body for selectively holding the bar in its groove and thereby holding the segment in its winding position while material is wound on the body and for releasing the bar so that it may be withdrawn from the groove after the material is wound on the body, whereby when the bar is removed from the groove the segment collapses toward the body and permits the arbor to be withdrawn from the material wound thereon.

4. An arbor for winding flexible material into coils, which comprises an elongated cylindrical body having opposed gaps in its winding surface and a transverse bore communicating with the gaps in said winding surface, an elongated segment positioned in one of the gaps and movable generally transversely with respect to the body between a collapsed position and an expanded position in which the outer surface of the segment forms a continuation of the winding surface of the body, a thrust element attached to the segment and mounted slidably in the bore for moving the segment with respect to the body, a second elongated segment insertable in the other gap in the body for forming a continuation of the winding surface of the body and for mov-

ing the thrust element in the bore so as to hold the first-mentioned segment in its expanded position, and means for selectively holding the second-mentioned segment on the body while the material is being coiled thereon and for releasing the segment so that it may be removed from the body after the material is wound thereon, whereby when the last-mentioned segment is removed from the body the first-mentioned segment collapses toward the body and permits the body to be withdrawn readily from material wound thereon.

5. An arbor for winding flexible material thereon, which comprises a rod having a pair of longitudinal grooves in its winding surface and a bore communicating with the grooves, an elongated segment positioned movably in one of the grooves and having a thickness less than the depth of said groove, a thrust member attached to the segment so as to pass through the bore and extending into the other groove in the winding surface of the rod, means insertable in said other groove for moving the thrust member and thereby moving the segment with respect to the rod, and means provided on the thrust element for limiting the movement of the segment with respect to the body so that the maximum movement of the thrust element positions the segment so that its outer surface is aligned with the winding surface of the rod.

6. An arbor for winding flexible material thereon, which comprises a rod having a pair of longitudinal grooves in its winding surface and a plurality of parallel, transverse bores communicating with said grooves, an elongated member positioned movably in one of the grooves and having a thickness less than the depth of said groove, a plurality of pins spacedly secured on the movable member so as to pass through the communicating bores and extend into the empty groove, and means insertable in the empty groove for moving the pins and thereby moving the member so that its outer surface is aligned with the winding surface of the rod.

7. An arbor for winding flexible material thereon, which comprises a body having a plurality of longitudinal grooves in its winding surface and a plurality of bores communicating with the grooves, an elongated member positioned movably in one of the grooves and having a thickness less than the depth of said groove, a plurality of pins spacedly secured on the movable member so as to pass through the communicating bores and extend into the empty groove, resilient means insertable in said empty groove for moving the pins radially and thereby move the member outwardly in its groove, means for limiting the outward movement of the member by the pins so that its outer surface is aligned with the winding surface of the body when the pin-actuating means is positioned in the groove, and means for selectively holding the pin-actuating means in its respective groove and releasing the pin-actuating means so that it may be withdrawn from said groove.

8. An arbor for winding flexible material thereon, which comprises an elongated cylindrical body having a plurality of longitudinal grooves in its winding surface and a bore extending transversely therethrough and communicating with the grooves, an elongated segment positioned in one of the grooves and movable generally transversely with respect to the body between a collapsed position and an expanded position in which the outer surface of the segment forms a continuation of the winding surface of the body.

ment forms a continuation of the winding surface of the body, a thrust element attached to the segment and mounted slidably in the bore so as to extend into the other groove in the winding surface of the body, means insertable in said other groove for clamping the end of the flexible material to the arbor and moving the thrust member to move the segment outwardly in its groove, and means provided on the thrust member for limiting the movement of the member in the bore so that when the actuating means is inserted in the groove the thrust member holds the segment so that its outer surface is flush with the winding surface of the body.

9. An arbor for winding flexible material into coils, which comprises a cylindrical body having a plurality of longitudinal grooves in its winding surface and a plurality of bores communicating with said grooves, an elongated segment positioned movably in one of the grooves, said segment having its outer surface curved to conform with the surface of the body and a thickness less than the depth of the groove in which it is positioned, a plurality of pins secured spacedly on the segment so as to pass through the communicating bores and extend into the empty groove, a bar insertable in said empty groove for actuating all the pins to move the segment outwardly in its groove and for clamping the end of the flexible material to the body, means provided on the pins for limiting movement of the pins so that the maximum movement thereof positions the segment so that its curved surface and the winding surface of the body form a perfect circle, and means for selectively holding the bar in its groove to maintain the segment in its outermost position while the material is wound on the body and for releasing the bar so that it may be withdrawn from its groove after the material is wound on the body.

10. A collapsible arbor, which comprises an

elongated rod having a pair of opposed longitudinal grooves in its winding surface and a plurality of parallel, transverse bores communicating with one of the grooves and counterbored portions thereof communicating with the opposite groove, a segment positioned movably in the groove communicating with said bores and having its outer surface curved to conform to the winding surface of the rod, the maximum thickness of the segment being less than the depth of said groove, a plurality of pins secured spacedly to the segment so as to slidably engage the bores, said pins having headed portions which slidably engage the counterbored portion of the bores and extend into the groove communicating therewith when the segment rests on the bottom of its groove, said pins being so designed that when the headed portions abut the bottom of the counterbores the segment is positioned in its groove so that its outer surface is flush with the winding surface of the rod, and a curved resilient bar insertable in the other groove for clamping the end of the material to the rod and for moving the pins until their headed portions abut the bottom of the counterbores and hold the segment in its winding position with respect to the winding surface of the rod.
